DESIGN FOR CHESSMEN

William F. Drueke, Grand Rapids, Mich.

Application June 9, 1941, Serial No. 101,358

Term of patent 14 years

To all whom it may concern:

Be it known that I, William F. Drueke, a citizen of the United States, residing at Grand Rapids, in the county of Kent and State of Michigan, have invented a new, original, and ornamental Design for Chessmen, of which the following is a specification, reference being had to the accompanying drawing, forming part thereof.

Fig. 1 is a perspective view of the king.

Fig. 2 is a perspective view of the queen.
Fig. 3 is a perspective view of the bishop.
Fig. 4 is a perspective view of the knight.
Fig. 5 is a perspective view of the rook.
Fig. 6 is a perspective view of the pawn, showing my new design.

I claim:

The ornamental design for chessmen, as shown.

WILLIAM F. DRUEKE.
